CLAIM

The ornamental design for a lantern, as shown and
described.

DESCRIPTION

FIG. 1 is a perspective view of the lantern showing my
design;

FIG. 2 is a right side elevational view thereof;

FIG. 3 is a front elevational view, thereof;

FIG. 4 is a top plan view, thereof; and,

FIG. 5 is a bottom plan view.

The left side of lantern is a mirror image of right side
elevation. The broken-line showing of environmental struc-
tures in FIGS. 1-5 is for illustrative purposes only and forms
no part of the claimed design.
